COMBINED DOOR JAMB AND PANEL FRAME MEMBER

Robert A. Miller, Plainville, Conn., assignor to The Stanley Works, New Britain, Conn., a corporation of Connecticut

Filed Apr. 22, 1968, Ser. No. 11,540

Term of patent 14 years

Int. Cl. D25—03

U.S. Cl. D13—6

FIG. 2

FIG. 1 is an end view of a combined door jamb and panel frame member showing my new design, the broken line showing of an extruded snap-in cover strip being for illustrative purposes; and

FIG. 2 is a perspective view of the combined door jamb and panel frame member of FIG. 1.

I claim:

The ornamental design for a combined door jamb and panel frame member, as shown and described.
